(76) Inventor: **Richard Tripe**

Richard Taaffe   Patented April 1st, 1806
Sellers Valent.

See Schedule annexed to this Letter Patent for a
copy of the same containing a description in the words
of the said Richard Taaffe himself of his Improvement
in a Drawing Machine.

To prevent the exhausting of the air, and
to prevent the weight, resistance and elasticity of the
air, and other fluid, which by ordinary means
would not have been effected, a pipe, tube or cyl-
inder, from 3 to 12 inches diameter, which extends along
the course where the service of the water is to be communicated,
at a depth of water, which passes the outer edge of
the machine, when an air-pump is put into the same near
the top, where a cock is opened to introduce an impulse the
current of air. On the bottom, which sustains the
whole machine, a pair of large Bellows are constructed,
when now a hand is inserted into the air-pipe, the
upper part of which is made fast with a proper cap-
stopper, which (Bellows) when worked force the air down
in such quantities as not only to supply the River
sufficient for the purpose.

whole mass of water from the inside of the
machine. By this means the machine is carried to the
bottom of the river, and it being intended that for that purpose
the machine is constructed of wood, shaped with broad
the back being fitted up by sheels or squares of
lignum-vitae inserted into the sides of the machine. The
machine is fasted or bound to means of a manfall,
which passes to a hook or Crotchet on the
Gondola, which being at the top of the River, and a man fall
to the same machine. Several lines are attached from

The inside of the machine is the surface of the water, or to any further distance. To keep the machine stationary from & braces are made fast to the top of the same and extend to the Gondola, or to any distance above it. The tube or Pipe from the inside of the machine to two or three feet on the outside is constructed of hard metal. The remainder of thick water-proof leather. Patented.
